BOOKKEEPING MACHINE

Emil Schneider, Mailand, Italy

Application November 9, 1931, Serial No. 573,993
In Germany June 9, 1931

1 Claim. (Cl. 101—288)

The invention relates to a power-driven book-keeping machine, for example adapted to be coupled at will by means of a foot-operated clutch or otherwise with an electric motor having a device for gripping the document to be written and advancing it line by line, the said document being held quite flat. In book-keeping certain words, word groups, numbers or number groups, are very often repeated. The object of the present invention is to simplify the writing of these often-repeated like words, and thereby to save time and avoid mistakes. This object is attained in accordance with the present invention by the provision of a line or group printing mechanism whereby a whole series of predetermined numbers or words can at once be printed, the numbers and words always being ready for printing. No time is therefore lost in setting up the words or numbers which are repeated, and no errors can thereby occur. The gripping or stretching apparatus for the document to be written can be so constituted that a plurality of copies can be obtained through carbon leaves.

The machines hitherto known do not operate satisfactorily and cannot be used for the purpose in view. The usual typewriters have the following drawbacks:

1. The adjusting of the paper on the roller is tedious and inconvenient,
2. Each word and each number at each repetition must be reproduced by numerous key actuations,
3. Entry of the words or groups of numbers in the correct columns, exactly in the correct positions, occupies a considerable amount of time.

The known flat writing machines, operating for example on the Elliot-Fischer system, are better suited for book-keeping. The known machines have however the drawback that with them also, each word and each group of numbers must be individually built up by means of numerous key actuations. Working with these machines is therefore slow, manipulation is inconvenient and the machines are expensive. Electrical adding machines, which are already known, also possess most of the drawbacks mentioned. With these machines entry in the columns is, indeed, facilitated, but only a limited number of columns can at any time be written at once.

It is furthermore often necessary to print a plurality of forms with the same text, individual forms, however, having certain parts of the text or numbers omitted. A further object of the present invention is to render possible this exclusion of text parts or groups of numbers without

readjustment of the type carriers. This object is attained in accordance with the present invention by providing in an adjustable impression plate towards which the type wheel carrier advances, recesses which can be adjustably positioned as desired in the printing position of the type wheel carrier, whereby certain groups of figures or letters are not printed on the forms. This new arrangement has the advantage that the work of adjusting the type carriers is simplified. In this way the output of the book-keeper is definitely increased.

The accompanying drawings show diagrammatically a constructional example of the machine. In the drawings:

Fig. 1 is a front elevation of the machine partly in section.

Fig. 2 is a plan.

Fig. 3 is a detail vertical sectional view of the stamping head mechanism.

Fig. 4 is a similar view of the same on another plane.

Fig. 5 is a detail vertical sectional view through the table disclosing the adjustable printing bed plate and associated mechanism.

Fig. 6 is a detail plan of the same.

Fig. 7 is a detail vertical transverse sectional view of the same on a plane disclosing one pair of the feed rollers and operating mechanism therefor.

Fig. 8 is a similar view disclosing the means for raising and lowering the roller 22.

Fig. 9 is a detail vertical transverse sectional view of the table, the adjustable printing bed, plate or element and the means for adjusting the latter.

Fig. 10 is a diagrammatic elevation of the roller controlling and operating means and looking from the right hand side of Fig. 6.

Fig. 11 is a detail diagrammatic elevation, partly in section, of the means for operating the inking band or ribbon.

Fig. 12 is a detail elevation at right angles to Fig. 11 of one of the inking band rollers and associated elements.

Fig. 13 is a diagram of the table, the feed rollers, the adjustable printing bed, the rollers for feeding the account sheet to be printed and also for feeding the carbon paper therewith together with the stamping head.

The machine illustrated is provided with a table 1 and two guides 2, 3 in which is guided in vertical tracks a type wheel carrier or stamping head 4. For raising and lowering the stamping head 4 there serves a

motor-driven crank shaft 5 and connecting rods 6. To connect the motor with the crank shaft 5 any suitable means such as a clutch may be provided, which is operated by a foot lever 86. Said lever 86 is fixed to a shaft 87 rotatably mounted in the frame of the machine. To shaft 87 an arm 87a is fixed which is connected by a link 88 to one arm of a bell crank lever 89. The second arm of said lever 89 operates a clutch connecting the motor shaft with gears driving crank shaft 5. The number of rotations are counted by a device 90 driven from crank shaft 5 by a rod 91. In the stamping head 4 the figure type wheels 8 are mounted in individually adjustable manner on a common shaft 7 while the word wheels move en bloc. The type wheels 8 are provided, in accordance with requirements, on their entire periphery or a part thereof, with letters and numbers, so that expressions such as "bills of exchange" or "drafts", "cash payment" etc., commonly occurring in book-keeping can be set up. The number of type wheels accords, in any given case, with the type of book-keeping form to be used, so that it is possible to imprint the text and number groups at predetermined positions on each form. Some of the type wheels 8 (say ten) are geared to toothed sector discs through intermediate toothed gears 8a, 8b. The discs 8c are mounted on a common shaft 8d within a casing and carry on their circumference the same types as the wheels 8. The sectors 8c are provided with handles 8e for rotating the gears 8b and 8a to set the desired type on the wheels 8 in printing position. The wheels 8 carrying members mesh with gears 9 provided on their periphery with numbers. The word to be printed appears through the window 10 on the appropriate sector disc 8c and the numbers in the openings 11 of the casing. The wheels 8c and therewith the wheels 8 may be turned manually by means of a knob on one end of the shaft 8d so that any one of the stock words may be brought in the position to be printed. In an opening in the table a plate 13 (Fig. 9) is displaceably arranged in guides 14. This plate is provided with recesses 16, 17. By adjusting the plate 13 one or other of the recesses 16, 17 can be brought beneath the printing position of the stamping head 4, whereby only certain of the whole text and number groups are printed. For adjusting the plate 13 (Fig. 9) into the position required at the time a rod 18 is used, the said rod being connected to a lever 19, which latter is pivotally mounted in the table 1. By adjusting the lever 19 the operator can adjust the plate 13 into any required position.

Some of the type wheels provided with numbers are adapted to be connected with a counting mechanism arranged on the stamping frame, by means of a connectible and disconnectible gearing, known per se, with tens transferring device, whereby the said counting mechanism, upon actuation, can add, or if desired subtract, a desired column of figures.

For feeding and advancing the documents two pairs of rollers 21, 22, 23, 24 are used; these are arranged at opposite sides of the impression plate 13. For driving the roller 22 there is used a gear 25, with which engages a toothed segment 26 rotatably mounted on the machine frame. The gear 25 is loosely mounted on a shaft 80 and is firmly connected with a disc 81 carrying a pawl 82. The pawl 82 engages a ratchet wheel 83 fixed on shaft 80. A gear wheel 84 is rigid on shaft 80 and

meshes with wheel 85 on roller 21 which is geared with roller 22. The wheel 25 which is rocked by the toothed segment 26 drives the shaft 80 and therewith the rollers 21, 22. The segment 26 is provided with an arm and a pin 27 on said arm; the latter engages in a slot 28 of a control link 29, which is pivoted on a pin 30 of a slide 32. The control link 29 is moved to and fro by one of the rods 6 moving the stamping head 4 up and down, said rod having a pin secured thereto as shown in Fig. 2, which pin operates in a slot 29a with which the member 29 is also provided. As a result the toothed segment 26 and with this the lower feed roller 21 are rotated. The latter transmits its rotation by means of the toothed wheels 33 to the lower roller 23. The two rollers 21, 23, which are of the same diameter, rotate with the same speed and serve in conjunction with the rollers 22 and 24 to feed forward the sheet of paper to be printed, to an extent corresponding to one line width for each operation of the stamping head 4. In order to adjust the magnitude of the advance movement of the sheet of paper, the angle by which the segment 26 is rocked is altered by varying the effective length of the link 29. The pin 30 about which the link 29 rotates is shifted with reference to pin 27. The bearing 31 for pin 30 is attached to a slide running in guides 34 on the underside of the table 1. The slide 32 may be adjusted by a two-armed lever 35 one arm of which projects through a slot in the table plate 1. To allow of insertion of the forms into the device at least one of the rollers 21, 22 must be moved. For this purpose the bearing of the roller 22 is arranged in a lever 36, which is pivoted about a pin 37. The roller 22 could, however, be supported at both ends, in which case it would have the same length as the roller 21. If the impact is effected only on the extreme left side, the support is at that end, if the impact is effected to the right a support at both ends must be used. The lever 36 is submitted to the action of a spring 38 and can be raised against the action of this spring by means of a two-armed lever 39, whereby it raises the roller 22. The lever 39 is provided with a knob 40 and projects through a slot in the table plate 1. By means of pressure on the member 40 the roller 22 is raised. A form for printing can then be inserted beneath the stamping head 4. The journal sheet, for example, of the forms to be printed is passed in between the rollers 23, 24, 21, 22 while the account sheet to be printed at the same time is only passed through the rollers 21, 22. In order that the roller 24 may be raised from the roller 23, the former is mounted in a lever 41; the latter being rotatably mounted in the table plate, under the action of a spring 42, so as to be displaceable against the action of this spring by means of a push rod 43 and a handle 44. The push rod 43 carries a roller which acts upon an inclined surface 45 of the lever 41. By displacing the handle 44 the roller 24 is raised. The paper can then be inserted between the rollers. In order to prevent the account sheets from being gripped by the roller 24 a guide 46 is provided on the lever 41.

As a journal sheet a sheet, or rather a band, 50 can be provided, Fig. 13, which is drawn together with a carbon paper band 51 from rollers 52 and is rolled up on rollers 53.

The stamping head 4 co-operates with an inking band, which can be introduced in any desired manner, for example as shown in Figs. 11 and 12. On the stamping head 4 the two inking

band rollers 55, 56 are arranged, on which the inking band 57 is rolled and unrolled. For effecting the advance movement wheels 58, 58' are used, which are respectively engaged by pawls 59, 59' each under the action of a spring. The advance movement is controlled by means of an advancing mechanism. The latter comprises a lever 60 pivotally mounted on the machine frame. A pin 66 of the lever 60 projects into a slot 61 in a rod 62. Into a slot 63 of this rod, there projects a pin on a bell-crank lever 64, the latter being connected to a rod 65 which co-operates with the pawl 59 as follows:

When the stamping head 4 moves downwardly, the rollers 55, 56 partake of the movement, as also do the members 65, 64, 62. Before the stamping head 4 reaches its lowermost position the rod 62 is stopped by the pin 66 of the lever 60. The rod 62 and therewith the levers 64, 65 becomes displaced relatively to the inking band rollers 55, 56. The pawls 59, 59' alternately drive their respective wheels 58 and 58' to wind and unwind the inking band from one wheel to the other in any of the suitable manners known in the art in connection with printing through an inking band. The extent of movement can be altered by means of an adjusting screw 70.

For adjusting the type wheels, hand-operated keys can be provided.

On the table there could also be provided an adjustable stop for the account sheets, in order to bring them into the correct position relative to the stamping head 4.

The words to be imprinted may be attached or engraved as a complete type block to the periphery of a drum, instead of being assembled by individual type wheels.

What I wish to claim and secure by U. S. Letters Patent is:—

Apparatus of the class described, comprising a table, a vertically movable stamping head, a printing bed on the table, a pair of rollers for feeding a sheet to be printed across and over the printing bed, one of said rollers being arranged on the upper side of the other and means to raise one end of the upper roller and comprising a vertically movable lever mounted in the table and having a bearing for said end of said roller, a spring active on said lever to normally hold the same and said end of said roller in lowered position and means to raise said lever and hence said end of said roller against the tension of said spring.
